UNITED STATES PATENT OFFICE

JAMES R. WYSONG, OF RICHMOND, VIRGINIA, ASSIGNOR TO LARUS & BROTHER CO.,
OF RICHMOND, VIRGINIA, A CORPORATION OF VIRGINIA

TOBACCO MEASURING AND FEEDING DEVICE

Application filed May 9, 1928. Serial No. 276,455.

My invention relates to a tobacco measuring and feeding device, and it is an object of the invention to provide a device of this character which is simpler in construction, cheaper to manufacture, more durable, which does the work more accurately, is more economical in operation, and requires less attention.

Referring to the accompanying drawings which are made a part hereof and on which 10 similar reference characters indicate similar parts,

Figure 1 is a perspective illustrating one application of my invention,

Figure 2, a perspective taken from a different angle and with parts removed,

Figure 3, a side elevation with parts removed, and

Figure 4, is a fragmentary vertical section.

In the drawings reference character 10 indicates a housing or casing supported upon legs 11 and 12 and provided at its bottom with a discharge chute 13 projecting downwardly between the legs for discharging tobacco therethrough. From the chute 13 a predetermined quantity of tobacco is received by a machine (not shown) of conventional construction. Said machine compresses the tobacco, wraps it in paper and inserts the package into a can.

30 The upper portion of the housing 10 is provided with an opening or inlet 14, into which the tobacco is discharged from a hopper 15 having a detachable mouth or bottomless receptacle 16, into which the tobacco is fed from a source of supply.

The housing 10 is provided with a drum 17 having a plurality of pockets 18 about its periphery which pockets are adapted to be filled with tobacco from the hopper 15 and 40 such tobacco discharged through the chute 13 when such pocket reaches the open upper end of the chute. The drum 17 has a central hub 19 which is fixed upon a shaft 20, said shaft having one end journalled in a bearing member 21, formed at one side of the housing 10, and at its opposite end journalled in a bearing 22, forming a yoke 23, having its upper and lower ends attached to the side of the housing 10, the lower extremity of the 50 yoke being provided with a portion adapted

to cooperate with the hopper 15 and legs 11 and 12, the upper extremity of the yoke being shaped to conform to the surface of the housing 10 and lower portion of the hopper 15. In this manner as the shaft 20 is rotated, the drum 17 will be rotated in a manner to cause the pockets 18 to pass beneath the hopper 15 and receive a charge of tobacco which will drop through the chute 13 when the pocket reaches the same.

Means is provided for rotating the shaft 20, which comprises a sprocket wheel 24 driven by means of a sprocket chain 25 from the machine (not shown) in proper timed relation therewith.

The hopper 15 is formed of a pair of spaced side plates 26 and a pair of front and back plates 27 detachably held together by bolts 28, the side plates 26 being provided with strengthening ribs or webs 29 in which are formed bearings 30 for an agitator shaft 31. The agitator shaft 31 is provided with a plurality of agitator pins or fingers 32, disposed relatively at different angles which when the machine is in operation rotate and engage the tobacco for causing it to flow in a constant stream into engagement with the periphery of the drum 17. The agitator shaft 31 is driven from a shaft 20, through the instrumentalities of a pair of sprocket wheels 33 70 and 34 mounted respectively on the shafts 20 and 31, and a sprocket chain 35 which extends about the same.

A pair of sprockets 36 and 37 are mounted respectively upon shafts 38 and bracket 39, 85 the sprocket 37 being nothing more than an idler, while the sprocket 36 is fixed upon the shaft 38 and serves to drive the same, such shaft being provided with agitator pins or fingers 38' in the bottom of the hopper 15 or inlet from the hopper to the housing 10. The agitator shaft 38 is located at one side of the opening 14 so that as soon as the front ends of the pocket 18 start to pass into position to be filled, said agitator will cause the tobacco to readily fall into the same. By this construction when the machine is operating the chain 25 will drive the shaft 20 carrying the drum 17, and the chain 35 driven from the shaft 20 will drive the agitator 95 100

shafts 31 and 38. Means is provided for varying the capacity of the pockets 18, so that they can be caused to discharge a larger or smaller quantity of tobacco, said means comprising a plurality of plungers 40 provided with outer surfaces curved in conformity with the inner peripheral wall of the housing 10 and each having a forward extremity curved in conformity with the cross section 10 of the pocket 18, the material being cut away toward the rear end of the plungers to provide a structure of relatively light weight, said plungers being adapted to be moved longitudinally within the pockets across the periphery of the drum for varying the length of the pocket.

The plungers 40 are carried by supporting straps 41 which are bolted to the peripheral flange 42 of the supporting disk 43 rotatably mounted upon the shaft 20.

The shaft 20 is provided with threads 44 adjacent the supporting disk 43 and a corresponding threaded hand wheel 45 is mounted upon such threaded portion, and upon rotation is adapted to be moved longitudinally of the shaft, such hand wheel having an annular slot 46 in which are located the inturned ends of a pair of pins 47 in threaded engagement with the disk 43 and held in fixed position by 30 lock nuts 48.

By this construction, when the hand wheel is rotated the disk will be moved axially along the shaft 20 carrying with it the plungers. A lock nut 49 is provided which is adapted to lock the hand wheel in the proper fixed position.

In machines of this character, one problem is to prevent the working parts from becoming gummed or clogged with tobacco and the 40 moistening solution which is supplied for giving it the proper treatment. Such gumming or clogging of the machine results in a rapid wearing of the parts of the same and requires the constant care of an attendant to 45 supply the necessary lubricant to the parts, and in some machines, the constant attention of an attendant is necessary with each machine, the attendant being required to squirt the lubricant constantly over the various 50 working parts.

In my device, however, I have taken a considerable step toward the elimination of the services of an attendant, one attendant being capable of caring for several machines, all of 55 which are capable of being kept constantly in operation, and the material is so accurately measured that a vast saving of time and material is effected.

As shown, I have provided a trap door 50 in one side of the housing 10, said trap door being formed of a segment of the peripheral portion of the housing which I have pivoted at one end upon a pin or bolt 51, and to the other end of which I have attached a closing 65 spring 52 for resiliently holding the trap

door in closed position, said spring being attached to a rod 53 on the door and to an eye 54 on the housing. To one end of the trap door are attached a pair of felt pads 55, held in place by a metal strap 56, such pads being adapted to receive lubricant supplied from a lubricant cup 57, through a tube 58 and branch tubes 59 through the trap door into diagonal grooves 60 on the interior of the same.

In the operation of the machine the lubricant cup 57 is supplied with the same kind of solution with which the tobacco is moistened in order to lubricate the periphery of the drum 17, such solution being supplied to the felt pads 55, and being applied to the periphery of the drum by the resilient pressure of the spring 52 which presses the pads against the periphery of the drum. In this manner the wear on the parts will be reduced to a minimum, or substantially eliminated. Since the parts fit so snugly gumming and the like will be prevented.

It will be obvious to those skilled in the art that various changes may be made in my device without departing from the spirit of the invention and I, therefore, do not limit myself to what is shown in the drawings and described in the specification, but only as set forth in the appended claims.

Having thus fully described my said invention, what I claim as new and desire to secure by Letters Patent, is:

1. A device of the class described comprising a housing, a rotary drum in said housing, provided with pockets in its periphery, a trap door in the housing, and moistening pads on the inner side of the trap door for moistening the periphery of the rotary drum, substantially as set forth.

2. A device of the class described comprising a housing, a rotary drum in said housing provided with pockets in its periphery, and means for moistening the periphery of the rotatable drum comprising a body curved in conformity with the periphery of the drum and provided with absorbent means on its inner surface, substantially as set forth.

3. A device of the class described comprising a housing, a rotary drum in said housing provided with pockets in its periphery, means for moistening the periphery of the rotatable drum comprising a body curved in conformity with the periphery of the drum and provided with absorbent means on its inner surface, and means for supplying lubricant to the absorbent material, substantially as set forth.

4. The combination of a cylindrical housing, a cylindrical drum rotatable in said housing and provided with pockets in its periphery, means associated with the drum for varying the capacity of said pockets; absorbent lubricant supplying means constantly engaging the periphery of the drum for 130

5 lubricating the same and for moistening the material in said pockets, a hopper mounted above said housing and having its lower end in communication therewith, agitating means in said hopper for causing material to be continuously fed into the pockets on the rotary drum, and a discharge chute in the bottom of the housing for receiving material from said pockets, substantially as set forth.

10 5. A tobacco measuring and feeding machine comprising a housing, a movable member in said housing having tobacco receiving pockets and means for supplying a lubricating and moistening solution to the wearing surfaces of the movable member and to the housing where it will be applied to the tobacco, said means including a body, and resilient means for pressing said body against the movable member, substantially as set forth.

15 6. A device of the class described comprising a housing having an inlet and an outlet, a movable member mounted in said housing provided with depressions forming tobacco receiving and measuring pockets, said housing having a removable section, and absorbent material carried by said removable section for moistening the edges of said pockets, substantially as set forth.

20 7. A tobacco measuring and feeding machine comprising relatively movable members, one of said members being provided with a depression forming a tobacco receiving and measuring pocket, and absorbent means 25 on one of the members engaging the other member for supplying a lubricating and moistening substance to said machine in a manner to lubricate the same so that excessive lubricant will moisten the material received 30 in the pocket, substantially as set forth.

40 In witness whereof, I have hereunto set my hand at Richmond, Virginia, this 7th day of May, A. D. nineteen hundred and twenty-eight.

45 JAMES R. WYSONG.
